JAMES R. MCWANE, OF BIRMINGHAM, ALABAMA.

MEANS FOR SUPPORTING CORE BARS IN FLASKS.

Application filed December 12, 1924. Serial No. 755,512.

To all whom it may concern:

Be it known that I, JAMES R. MCWANE, a citizen of the United States, residing at Birmingham, in the county of Jefferson and

5 State of Alabama, have invented a new and useful Improvement in Means for Supporting Core Bars in Flasks, of which the following is a specification.

This invention relates to means for supporting core bars in flasks.

The object is to provide means for rigidly supporting core bars of elongated form in flasks, such as are used in the manufacture of pipe or analogous castings by the 15 horizontal method, wherein the flasks are placed on the molding floor in horizontal position for the reception of the molten metal, and wherein it is necessary that the core bar, together with the sand core thereon, shall occupy a true concentric position 20 in the mold throughout its length, in order to secure a casting of uniform thickness.

Another object is to provide means for this purpose that shall firmly grip the core 25 bar beyond the ends of the mold, and to effectually prevent any sagging of the intermediate portion of the core bar and core due to the weight thereof, and also to prevent any rising movement of the same due 30 to the floating action of the inflowing molten metal when the same is poured.

A final object is to provide means which will accomplish the above stated purpose without the necessity for using chaplets to support the core bar at intervals, and which 35 are necessarily left embedded in the wall of the casting, the means herein employed being designed to be readily attached to existing flask sections, such as are in use in horizontal pipe casting operations without 40 the necessity for any alterations in the same, or the invention may be readily incorporated as an integral part of new cope and drag sections, without interfering in any 45 manner with the present functions of the same.

A full and complete understanding of the invention may be obtained from a consideration of the following detailed description, 50 taken in connection with the accompanying drawings forming a part of this specification, it being understood that while the drawings show practical forms of the invention, the latter is not to be confined to strict 55 conformity with the showing thereof, but may be changed or modified, so long as such

changes or modifications mark no material departure from the salient features of the invention, as specifically pointed out in the appended claims.

60 In the drawings, in which similar reference characters designate corresponding parts throughout the several figures:—

Figure 1 is a longitudinal view, illustrating diagrammatically the principle involved 65 in one form of the invention;

Figure 2 is a similar view of another form;

Figure 3 is a vertical longitudinal section 70 through a double pipe molding flask used in the horizontal method of casting and showing a core bar and core supported therein by the improved means;

Figure 4 is an enlarged end view of the 75 same;

Figure 5 is a transverse sectional view thereof;

Figure 6 is a plan view of the subject matter of Fig. 4, the upper or cope section being removed and showing the ends of the 80 core bars, as used in a double flask, supported in the drag section by the improved means;

Figure 7 is a horizontal section taken on the line 7—7 of Figure 5;

Figure 8 is a detail perspective of one of the outer end supports for the core bars removed from the drag section of the flask;

Figure 9 is a similar view of one of the inner abutments removed from the cope section of the flask;

Figure 10 is a detail section showing the manner of mounting the set screws carried by the abutments;

Figure 11 is a detail perspective of one 95 of the wedges used in connection with the outer supports;

Figure 12 is an end view of a simplified form of end support;

Figure 13 is a detail section taken on the 100 line 13—13 of Figure 12;

Figure 14 is a detail perspective view of one of the members shown in Figure 12;

Figure 15 is a partial vertical longitudinal section similar to Fig. 3, but embodying 105 the modification of Figure 2.

In the drawings there is illustrated a complete flask 1 used in the manufacture of cast iron pipe, the said casting being done with the flask located on the floor of the 110 foundry and in a horizontal position. The flask comprises the lower section or drag 2,

and the upper section or cope 3, each of which is substantially identical in form, the cope being adapted to be superimposed, in reverse relation, upon the drag, after the 5 sand molds have been made therein, and the core bar 3^a, having the sand core thereon, has been placed in longitudinal position within the same.

Each flask section is provided with end 10 walls 4 of the form shown (although any other form may be employed), and a plurality of intermediate webs 5 spaced substantially equal distances apart throughout the lengths of the sections, said webs being 15 preferably formed integrally therewith and serving to strengthen the structure and to hold the sand therein.

The end walls 4 are preferably inclined slightly, as shown in Figure 3, and are provided with a pair of lifting arms or trunnions 6 at each end of each section, one of said arms or trunnions being longer than the other to facilitate turning of the section, or inverting the same while suspended in the 25 looped ends of lifting cables. This feature is claimed in my pending application, filed August 25, 1924, Serial No. 734,002.

Adapted to be secured to the outer faces of each end wall 4 of the lower or drag section 30 of the flask, is a cast metal bracket or plate 7 formed preferably of iron and partaking of the shape of the letter W, there being two V-shaped branches joined together and provided with an attaching flange 8 located at its lower and inner edge. The flange 8 is provided with a plurality of bolt openings 8^a for the reception of set screws 8^b, which rigidly secure the brackets in position on the outer faces of the end walls 4.

40 Each arm of the V-shaped branches is provided with an elevated face or pad 10 formed integrally therewith and extending upwardly and inwardly toward each other, each face being substantially at an angle of 45° to a vertical line through the axis of the core bar 3^a, and equidistant from the same. At the outer ends, each bracket 7 is provided with arcuate recesses 11, which are adapted to rest upon the aforesaid arms or trunnions 45 6, the latter being round in cross section, and thus strengthening the support of the bracket. The brackets 7 may, however, be otherwise held in position on the end walls, as by welding or brazing the same, as will be 50 readily understood.

60 Tapered wedges 12 are adapted to be driven in between the active faces of the pads 10 and the adjacent extending ends 13 of the core bar 3^a, where the same project through the openings 4^a formed in the end walls 4 of each of the flask sections, after the said core bar has been applied in position, in a manner to be explained.

65 The transverse web 5 next adjacent to the end walls 4 in the upper or cope sections, is

each adapted to support a casting or plate 14 formed to fit transversely within the cope, and having the necessary semi-circular openings 15 formed in their lower edges to correspond with the openings 5^a of the webs, 70 and adapted to receive and accommodate the core bar and core, as clearly shown in Figure 5 of the drawings. The lower outer corners of the plate 14 are cut away at an angle, as at 16, to fit against the abutting flanges 17 formed in both the cope and the drag and to thus receive additional support. 75

Located substantially over the centers of the openings 15 of the said plate are vertically disposed slots 18, which are adapted to receive the tap screws or bolts 19 threaded into the adjacent web 5, the slots permitting of more readily assembling the plate in position and seating the same upon the flanges 17, after which the screws are tightened. 80

85 Outstanding lugs 20, formed integrally with the plate, extend outwardly in angular relation to each other and at substantially 45° to the axis of the core bar, said lugs being suitably apertured and threaded for the reception of set screws 21, carrying swivelled heads 22 adapted to bear upon the core bar, when turned inwardly, to hold the same down, and at the same time prevent any lateral movement thereof. The wedges 12 90 act to hold the ends of the core bar up and also prevent any lateral movement thereof.

95 When the lower or drag section of the flask is properly rammed on the molding machine to form the mold therein and removed to the casting floor, the core bar 3^a with the core already formed thereon, is then positioned in longitudinal alignment with the lower half of the mold in the drag 100 and lowered to rest upon the hard packed sand within the end pockets of the drag between the end walls and the first webs. The cope with the complementary half of the mold formed therein is then lowered into 105 position, the flanges 17 abutting entirely around the two members and supporting the weight of the upper section, and the cope and the drag are locked together. The set screws 21 are then turned to contact tightly with the core bar, which may be readily done by removing a portion of the sand over the innermost screws while the outer screws 21 may be easily reached through openings 23 formed in the walls of the cope section and the wedges 12 are then driven into position 110 115 120 125 as described. One of the inner lugs 20 is longer than the other so as to permit of the application of a wrench without interference, as clearly shown in Fig. 7 of the drawings.

130 By reference to Fig. 1 of the drawings, it will be seen that the force of the inflowing metal, as indicated by the arrow, tends to raise or float the intermediate portion of the core bar where unsupported within the mold,

even though said bar be of a larger diameter and sufficiently stiff to support its own weight without sagging. This upward tendency of the intermediate portion is directed against the set screws which constitute abutments 22, as indicated in Fig. 1 and the result is that the outer end portions of the bar where projecting beyond the abutments are forced to act as levers imparting a downward tendency to the ends of the bar, but this downward tendency is effectively resisted by the wedges 12, with the result that the bar is rigidly held throughout its length and caused to lie concentric with the mold, and thus insure a uniform thickness of the wall of the casting.

Where smaller diameter core bars are considered and which might sag by their own weight, double sets of wedges 12 and double sets of abutments 22 may be employed, as indicated in Figures 2 and 15; it being readily understood that the arrangements already described may be duplicated in both the cope and the drag sections for this last-named purpose, to counteract both the upward pressure of the molten iron and the downward effects of sagging, as indicated by the arrows in said figure.

The heads 22 of the set screws are diametrically opposite the coacting wedges, as shown in Fig. 4, and thus the bending action of the bar is resisted in all directions, and this is essential, inasmuch as in pouring the molten metal in double flasks, such as illustrated in the drawing, the said metal enters in centrally disposed sprue holes or gates arranged in a longitudinal series, one for each pocket between the webs 5, and then passes through laterally disposed gates to the molds at different points along their lengths, so that the metal tends also to force the core bar outwardly as well as upwardly.

In Figures 12, 13 and 14 there is shown a simple form of the invention, wherein the wedges are dispensed with, and the supports are in the form of two identical plates 24 having semi-circular openings or seats 25 for receiving and supporting the ends 13 of the core bar, said seats being elevated above the cut-out portions 4^a of the end wall 4 of the lower or drag section 2. The plates are provided with vertical slots 26 for the reception of screws 27 entering the end wall, and serving in addition to dowel pins 28 to hold the plate to the section, and to support the weight of the core bar, the said plates being further provided with arcuate seats 29 adapted to rest upon the aforesaid lugs or arms 6.

From the foregoing it will be seen that a simple, strong and durable means has been provided for easy attachment to cope and drag sections of pipe molding flasks or other flasks for supporting the core bars in alignment with the mold, and to positively pre-

vent the movements thereof incident to the effects of sagging and from the floating effects of the inflowing molten iron, the said means being arranged in positions so as not to interfere with the placement of the cores 70 or with the application of the cope section to the drag.

What is claimed is:

1. In means for supporting a core bar in a pipe flask without the use of chaplets, outer supports bearing beneath the bar at the ends thereof, inner abutments bearing on top of the bar adjacent to and spaced from said supports, and wedges adapted to be inserted between the ends of the bar and the supports to insure close contact with the abutments and prevent any upward movement of the intermediate portion of the bar and consequent downward movement of the ends thereof.

2. In molding flasks, a core bar having a core thereon, a pair of spaced end supports carried by each end of the drag section of the flask to support the weight of the core bar and to prevent any downward and sidewise movement of the ends of the same, and a pair of spaced abutments carried by each end portion of the cope section of the flask and contacting with the core bar in longitudinal spaced relation to said supports to prevent any upward and sidewise movement of the intermediate portion of the core bar.

3. In means for supporting a core bar in a flask for casting pipe or the like, outer pairs of supports adapted to bear beneath and on top of the core bar at the ends thereof, and inner pairs of abutments adapted to bear beneath and on top of the core bar in spaced relation to the supports to prevent movement of the intermediate portion of the core bar in any direction, said supports and said abutments contacting with the core bar beyond the ends of the core.

4. In means for supporting a core bar in a flask for casting pipe or the like, upper and lower supports carried respectively by the cope and drag sections of the flask and located adjacent to the ends of the core bar, wedges interposed between the same and the core bar to bind the same, and upper and lower abutments carried respectively by the cope and drag sections and contacting with the bar adjacent to and between the supports to prevent movement of the intermediate portion of the same.

5. Means for supporting core bars in flasks, comprising a combined bottom and side support adjacent to the end thereof, and an abutment bearing on the top and sides of the bar and spaced at a distance from the lower support to constitute a fulcrum when the pressure of the inflowing iron causes the terminal portion of the bar to act as a lever and to prevent side move-

ment as well as upward movement of the central portion of the bar.

6. Means for supporting core bars in flasks, comprising combined bottom and side supports located adjacent to the ends of the bar, and abutments bearing on the top and sides of the bar at a distance from the supports to constitute fulcrums when the pressure of the inflowing iron causes the terminal portions of the bar to act as levers and to prevent side or upward movements of the central portion of the bar.

7. Means for supporting a core bar in a flask comprising upper and lower coacting clamping means located near the ends thereof, and upper and lower opposed abutments bearing on the bar in spaced relation to said clamping means, the lower abutments acting as fulcrums for the tilting ends of the bar when the central part of the latter tends to sag through its weight, such tilting being prevented by the upper clamping means.

8. Means for supporting a core bar in a flask comprising upper and lower coacting clamping means located near the ends thereof, and upper and lower opposed abutments bearing on the bar in spaced relation to said clamping means, the lower abutments acting as fulcrums for the tilting ends of the bar when the central part of the latter tends to sag through its weight, such tilting being prevented by the upper clamping means, and the upper abutments acting as fulcrums for the tilting ends of the bar when the central part of the latter tends to rise from the pressure of the inflowing metal, such tilting being prevented by the lower clamping means.

9. Means for supporting core bars in flasks without the use of chaplets comprising plates adapted to be secured to the outer faces of the end walls of the lower or drag section of the flask, each plate having opposed faces for the reception of wedges to bear against the undersides of the projecting ends of the core bar and constituting supports therefor, other plates adapted to be secured in the upper or cope section of the flask, and adjustable set screws mounted in said plates and adapted to contact with the upper sides of the core bar in spaced relation to the supports to prevent the intermediate portion of the bar from rising by floating on the molten metal.

10. Means for supporting core bars without the use of chaplets comprising brackets adapted to be secured to the ends of existing drag sections of flasks, said brackets having inclined, opposed faces below and equidistant from the axis of the core bar openings in the end walls, wedges adapted to be driven in between the faces and the projecting ends of the core bar to support the same, plates adapted to be secured to one of the transverse webs of existing cope sections of

flasks, said plates having inclined, opposed lugs arranged above and equidistant from the axis of the core bar opening in the web, and inclined set screws mounted in the lugs and adapted to bear down on the core bar adjacent to the supports to resist bending of the core bar through the action of the incoming metal.

11. Means for supporting, without the use of chaplets, core bars in pipe flasks, composed of lower or drag sections and upper or cope sections, said means comprising brackets adapted to be secured to the outer faces of the end walls of the drag sections and having a pair of inclined pads or faces arranged at an angle of substantially 45° to the axis of the core bar and below the same, other brackets adapted to be transversely secured in the cope sections in spaced relation to the pads or faces and having inclined lugs provided with adjustable set screws arranged at an angle of substantially 45° to the axis of the core bar and adapted to bear down on the same, and wedges adapted to be driven in between said pads or faces and the core bar in opposition to the set screws to prevent vertical or lateral movement of the bars.

12. Means for supporting, without the use of chaplets, core bars in pipe flasks, composed of lower or drag sections and upper or cope sections, said means comprising brackets adapted to be secured to the outer faces of the end walls of the drag sections and having a pair of inclined pads or faces arranged at an angle to the axis of the core bar and below the same, and wedges adapted to be driven in between said pads or faces and the core bar to prevent vertical or lateral movement of the bar.

13. Means for supporting core bars in flasks without the use of chaplets comprising brackets transversely mounted in the cope section and having inclined lugs, and set screws mounted in said lugs at an angle to the axis of the core bar and adapted to bear on the same.

14. Means for supporting core bars in flasks without the use of chaplets comprising brackets transversely mounted in the cope section and having inclined lugs, some of said lugs being larger than others, and set screws mounted in said lugs at an angle to the axis of the core bar and adapted to bear on the same.

15. Means for supporting core bars in pipe flasks without the use of chaplets, comprising a plate mounted on one section of the flask and having substantially semi-circular openings or seats at the inner edge where the flask section joins with the other section of the flask, and means for adjustably mounting said plate to the end wall of said flask section.

16. Means for supporting core bars in pipe

flasks without the use of chaplets, comprising a plate mounted on one section of the flask and having seats at the inner edge where one flask section joins with the other flask section, said seats supporting the extended end of the core bar and resisting downward movement of the same, and other seats provided on the plate and engaging with the lifting trunnions of the flask.

17. In means for supporting core bars in flask sections, wedge seats carried on the outer faces of the ends of the drag, said seats being arranged at opposite angles beneath and in spaced relation to the core bar, wedges adapted to be driven inwardly and downwardly between the seats and the core bar to support and prevent side movement of the core, inclined lugs carried by the cope in spaced relation to the ends thereof and in spaced relation to the core bar, and set screws threaded through the lugs and directed inwardly and downwardly at opposite angles to bear on the core bar and hold same down upon the supporting wedges and prevent side movement thereof.

flask sections, wedge seats carried on the outer faces of the ends of the drag, said seats being arranged at opposite angles beneath and in spaced relation to the core bar, wedges adapted to be driven inwardly and downwardly between the seats and the core bar to support and prevent side movement of the core, inclined lugs carried by the cope in spaced relation to the ends thereof and in spaced relation to the core bar, and set screws threaded through the lugs and directed inwardly and downwardly at opposite angles to bear on the core bar and hold same down upon the supporting wedges and prevent side movement thereof.

In testimony, that I claim the foregoing as my own, I have hereto affixed my signature.

JAMES R. MCWANE.
